UNITED STATES PATENT OFFICE.

TIMOTHY F. HORAN, OF COOPERSTOWN, NEW YORK.

CORNICE-MOLD.

1,149,367.

Specification of Letters Patent.

Patented Aug. 10, 1915.

Application filed March 27, 1912. Serial No. 686,715.

To all whom it may concern:

Be it known that I, TIMOTHY F. HORAN, a citizen of the United States, residing at Cooperstown, in the county of Otsego and 5 State of New York, having invented certain new and useful Improvements in Cornice-Molds; and I do hereby declare that the following is a full, clear, and exact description thereof, which will enable others skilled in 10 the art to which it appertains to make and use the same, reference being had to the drawings herein and to the reference-numerals marked thereon, which form part of this specification.

15 My present invention relates to cornice molds.

The purpose of this invention is to provide an improved article of the class described and one which is convenient and efficient in use and particularly adapted to perform good work in the forming of angles or 20 corners of cornices.

Figure 1 is a plan view of a cornice mold embodying my invention. Fig. 2 is a side 25 elevation thereof, as the same is seen when looking directly toward one of the edge guides.

Referring to the drawings in a more particular description: it will be seen that the 30 cornice mold has an irregular shaped frame composed of two sides 3 and 4 connected by a forward brace 5 and a rearward brace 6. On line with each other and bisecting the angle formed by the sides 3 and 4, there are 35 provided upon the forward and rearward braces 5 and 6 respectively, upstanding forked clamping plates 7 into the forks or slots of which is inserted a blade holder 8 conveniently formed of wood with a slot 14 40 in its upper edge into which is inserted the molding blade 9 with its edge of desired conformation, according to the pattern of cornice to be made, and projecting from the blade holder toward the working corner of 45 the device.

The device here shown is adapted to be readily changed to obtain different forms of cornices by having the blade and blade holder readily removable from the device 50 and another blade holder with its blade of proper form readily secured in the frame by means of thumb screws 10 extending through both parts of each pair of upstanding clamps 7 and through perforations in 55 the blade holder.

Upon the sides 3 and 4 of the frame are secured the edge guides 11 and 12 respectively, which are illustrated in the drawings as arranged at right-angles to each other, as that is the usual arrangement for a cornice 60 mold to be used in rectangular rooms. It will be obvious for special work that the angle between the edge guides 11 and 12 may be greater or less than a right-angle to fit irregular rooms or bay-windows and similar 65 places. These edge guides are spaced from each other and from the blade holder 8 and blade 9 at their near ends, or, in other words, do not extend to the vertex of the angle formed by said edge guides. This feature 70 enables my tool to be moved clear into the corner formed by converging walls or to be thrust into said corner and moved in either direction thus forming or cutting a sharp reentering angle at the corner. In working 75 with such a tool, small particles of the plaster or other plastic material being molded are apt to accumulate in front of the blade or in front of the end of the edge guide toward the blade. By leaving this clearance 80 between the near ends of the edge guides sufficient space is left for these particles or small pieces of plaster or other material and their presence does not prevent the cornice mold from working entirely into the corner 85 or working from the innermost point of the corner outwardly.

The portions of the rear brace 6 to each side of the blade may be shaped into convenient handles or may be shaped to receive 90 thereonto wooden handles 13 as plainly indicated in the drawings.

It will be obvious that various changes and modifications may be made in the device herein illustrated and described without departing from the spirit of my invention. 95

I claim—

1. The combination in a cornice mold of a frame, a pair of edge guides attached to 100 the frame and arranged at an angle to each other but having their near ends spaced from the vertex of the angle formed thereby and a vertically arranged molding blade removably secured on said frame bisecting the 105 angle formed by said edge guides and extending into the vertex of said angle.

2. The combination in a cornice mold of a frame, a pair of edge guides attached to the 110 frame and arranged at an angle to each

other but having their near ends spaced from the vertex of the angle formed thereby, a pair of oppositely disposed parallel clamping plates mounted on said frame and bisecting the angle formed by said edge guides and a vertically disposed molding blade removably secured between said clamping

plates and extending to the vertex of said angle.

TIMOTHY F. HORAN.
